J. L. DOSTAL

LAMPBLACK BURNER

Filed Feb. 17, 1923

FIG. I

FIG. II

JOSEPH LOUIS DOSTAL
INVENTOR.

BY
Stanley McVdale
ATTORNEY.

UNITED STATES PATENT OFFICE.

JOSEPH LOUIS DOSTAL, OF DETROIT, MICHIGAN, ASSIGNOR TO EARL HOLLEY, OF DETROIT, MICHIGAN.

LAMPBLACK BURNER.

Original application filed September 27, 1922, Serial No. 590,913. Divided and this application filed February 17, 1923. Serial No. 619,557.

To all whom it may concern:

Be it known that I, JOSEPH LOUIS DOSTAL, a citizen of the United States, residing at 8530 Dexter Boulevard, Detroit, in the county of Wayne and State of Michigan, have invented certain new and useful Improvements in Lampblack Burners, of which the following is a specification.

This invention relates to an improved burner for the uniform deposition of lamp black upon working surfaces of iron molds.

Figure I shows a cross sectional elevation of the burner.

Figure II shows the application of this burner to the mechanism described in my co-pending application, Serial No. 590,913, filed September 27, 1922, from which this application is divided.

In Figure II, KK represents a pair of co-acting molds which are to be protected by a coating of lampblack. These molds KK are mounted on a rotating table Z and are mechanically opened at a predetermined point in the revolution of the table to admit the burner P which is suspended from the shaft G by means of a bearing M. Gas is admitted to the burner P through the bearing M, which is hollow, and the pipe O. The shaft G, which serves as a pivot on which the burner P oscillates, is bolted by means of the bearing H to the cage S, which in its turn is provided with four wheels CC and DD. These wheels run on a track A and are carried with the moving molds K by means of the arm I which in its turn engages with the projection J from the mold K. The track A is inclined in such a manner that the burner P is raised as it is rotated with the molds K. When the arm I escapes from engagement with the projection J gravity returns the burner P to engage with the next succeeding pair of molds on the rotating table Z. Another track B is provided which is undulating and with this track B arm F and roller E engage. This arm F

is locked to a shaft G hence not only does the burner P travel with the molds KK but it is also raised up slightly and oscillated whilst it is being so raised. The purpose of all this mechanism being to get a uniform 50 coating but the details of this are covered in the above mentioned co-pending application.

A hydrocarbon gas rich in carbon, for example acetylene, is conveyed to the burner through the pipe N and pipe O and descends through the passage X to the bottom of the burner and rises through pipes T and discharges through the burners R, which are threaded into the burner P. The purpose of 55 60 the mechanism shown above in Figure II is described in the above mentioned co-pending application.

Operation.—The fact that the gas descends in O, through X, ensures that the maximum pressure exists at the bottom burner so a uniform desposition of lamp black is secured. If the descending passage X were omitted the upper burners would receive an excessive, and the lower burners 70 would receive only an inadequate, supply of gas and a uniform coating of lamp black would not be secured, which is the purpose of this invention.

What I claim is:

1. In a burner for depositing lamp black on the surface of molds, a downwardly extending passage, a plurality of upwardly extending passages connected to said downwardly extending passage, a plurality of 80 burners located in said upwardly extending passages.

2. In a burner for depositing lamp black on the surface of molds, a downwardly extending passage, an upwardly extending passage connected to said downwardly extending passage, a plurality of burners located in said upwardly extending passage.

In testimony whereof I affix my signature.
JOSEPH LOUIS DOSTAL.
